UNITED STATES PATENT OFFICE.

CHARLES W. WADSWORTH, OF MERRICK, NEW YORK, ASSIGNOR TO T. FRED. MOORE,
OF NEW YORK, N. Y.

DISPLAY DEVICE.

Application filed May 13, 1922. Serial No. 560,521.

To all whom it may concern:

Be it known that I, CHARLES W. WADSWORTH, a citizen of the United States, residing at Merrick, in the county of Nassau and State of New York, have invented certain new and useful Improvements in Display Devices, fully described and represented in the following specification and the accompanying drawings, forming a part of the same.

10 This invention relates to display devices, and aims to provide a simple easily adjustable foldable device for holding flat a flexible poster or a portion or panel thereof.

15 An object of the invention is to provide a device of this character which may quickly and easily be placed in display position without danger of tearing the poster, and readily folded for transportation.

20 A further object of the invention is to arrange the parts of the device so as to eliminate danger of accidental displacement of them after the device has been placed in display position.

25 A device constructed in accordance with the invention comprises a foldable stretching member having its ends pivoted to edge strips secured along opposite edges of a flexible poster or of a part or panel of such

30 a poster. The foldable stretching member consists of two or more normally straight pieces or sections pivotally connected together, one at least of which is flexible and resilient, so as to make the stretching member as a whole flexible and resilient. The total length of the stretching member between its end pivots when extended is slightly greater than the straight line distance between the pivots when the poster is 35 stretched flat so that the stretching member is bowed outwardly from the poster when extended. The tendency of the stretching member to reassume a straight position causes an outward thrust on the edge piece sufficient to stretch the poster, or the portion 40 of the poster between them, flat, without danger of tearing it.

45 The pivotal connections at the ends of the stretching member retain these ends in proper relation to the edge pieces while the stretching member is being placed in extended position so that this operation may be effected quickly without danger of one of the ends slipping and piercing the poster.

50 55 A further feature of the invention con-

sists in extending one or both of the connected ends of the pieces of the stretching member beyond the pivot so as to overlap the adjacent piece when the member is extended. The overlapping ends of the pieces 60 add to the strength of the stretching member and may serve also to prevent accidental displacement of the member when in extended position.

65 In order that the invention may clearly be understood, I will describe in detail the embodiments of it which are illustrated in the accompanying drawings.

70 Figs. 1, 2 and 3 show the application of the invention to a poster having three panels and vertical edge strips. Fig. 1 is a plan view of the device in display position; Fig. 2 is a perspective rear view of the device in display position, showing in dotted lines the position of the parts when the device is 75 partly folded; and Fig. 3 is a perspective view of the device in loosely folded position.

75 Figs. 4 and 5 illustrate the application of the invention to a one panel poster having horizontal top and bottom edge strips. Fig. 80 4 is a rear perspective view of the device in display position; and Fig. 5 is a perspective view of the device in loosely folded position.

85 The embodiment of the invention illustrated in Figs. 1, 2 and 3 will first be described. The device includes a flexible poster may be of any suitable material, such as paper or fabric. On the front side of the poster, that is, the side opposite to that shown in Fig. 2, display matter is printed or otherwise displayed. To the back of the poster along the edges of its portions or panels 10, 10, 10 are secured a plurality of pairs of parallel spaced edge strips 11 and 12. In the particular device illustrated in the drawings, these strips are of wood. They may, however, be made of other material. So far as the operation of the device is concerned, they are rigid.

90 95 100 105 110 Cooperating with each pair of edge strips 11 and 12 and each panel 10 of the poster, is a stretching member 13. In the form illustrated each stretching member 13 consists of two overlapping and pivotally connected pieces or sections 14 and 15. The outer ends of the pieces 14 and 15 are connected to the edge strips 11 and 12 respectively by parallel pivots 16 and 17 perpendicular to the edge strips. The pivot 18 connecting the 110

overlapping ends of the pieces 14 and 15 is parallel to the pivots 16 and 17 when the pieces 14 and 15 are not bowed. The overlapping ends 19 and 20 of the pieces 14 and 15 are most desirably extended substantially beyond the pivot 18.

Both pieces 14 and 15 of each stretching member 13 in the device shown are normally straight, flexible and resilient. They may 10 conveniently be formed of strips of wood. They are of the same length between their pivot points so that the edge strips 11 and 12 of each panel 10 may be brought evenly together by folding their stretching member 13 as illustrated in Fig. 3.

The total length of each stretching member 13 between its end pivots, when extended, is greater than the straight line distance between the pivots when the poster is 20 stretched flat, so that each stretching member, when extended, is bowed outwardly from the poster, as best seen in Fig. 1.

A sliable clip 21 may be placed around the underlapping strip 14 of each stretching member 13 for a purpose hereinafter explained.

The use of the device described is as follows:—

When the device is to be transported the 30 corresponding edge strips are brought together by folding the stretching members to lie against the edge strips as illustrated in Fig. 3, and the three panels of the poster are folded or rolled about the edge strips and 35 stretching members.

When the device is to be placed in display position, each panel is partially opened up by separating its edge strips, bringing the two pieces of its stretching member into the 40 position shown by dotted lines in Fig. 2. Each panel is then stretched flat by pressing down the middle portion of its jointed stretching member. This brings the stretching members into extended position as shown 45 in Figs. 1 and 2, in which position they are each bowed outwardly from the poster. The pivots serve to guide the stretching members when they are pressed from the positions shown in dotted lines in Fig. 2 to extended position, and thus make this operation 50 quick and easy; and the permanent pivoting of both ends of each stretching member to two edge strips with which it contacts eliminates the possibility of the piercing 55 of the poster by one of the ends of the stretching member in setting up the poster.

After each panel 10 of the poster has been stretched flat, the poster may be made to stand erect by swinging the two end panels 60 forward out of the plane of the middle panel as illustrated in Fig. 2. The adjacent edge strips of adjoining panels of the poster are hinged together, the hinge being formed in the construction shown by the narrow portions 65 of the poster between them.

When each stretching member 13 has been placed in extended and bowed position, the underlapping end 19 of its piece 14 presses against its outer piece 15 and frictionally resists relative turning of the pieces 14 and 15 about the pivot 18 and thus tends to prevent accidental displacement of the stretching member. Such displacement may, however, be positively prevented by sliding the clip 21 along the inner or underlapping piece 75 14 and over the end of the overlapping end 20 of the outer piece 15. The tension of the end 20 then holds the clip 21 in position, and the clip positively prevents any angular displacement of the pieces 14 and 15. The extended overlapping ends 19 and 20 add to the strength of the stretching member while the clip 21 relieves the strain on the pivot 18.

The device shown in Figs. 4 and 5 is in general similar to one of the panels 10 of the poster shown in Figs. 1 to 3, and the parts cooperating therewith. In Figs. 4 and 5, however, the edge strips 111 and 112 are horizontal and two jointed stretching members 113 are provided; and the device is also 90 provided with props 125 which serve to hold the poster upright when it is stretched flat by the stretching members. The props are pivotally connected at their upper ends to the upper edge strip by the pivots which connect the upper ends of the stretching members to the edge strip, so that the props when the device is folded may extend parallel to the edge strip, and when the device is set up in display position will extend away 100 from the poster in a direction tangential to the upper ends of the bowed stretching members.

Devices embodying the invention may be used for the display of pictures, photographs and printed matter of all kinds, all of which are intended to be included in the term "poster" in the claims following.

It is to be understood that the invention is not limited to the specific embodiments which have been described, and that certain features of the invention which are combined in the embodiments illustrated may under some conditions be advantageously used separately.

What is claimed is:

1. The combination with a flexible poster, of spaced edge strips, and a stretching member consisting of a plurality of pieces which are permanently connected together 120 and permanently connected to said edge strips by pivots approximately perpendicular to the edge strips, the stretching member being flexible in the plane of the pivots, resilient, normally straight, and bowed outwardly from the poster so that it exerts a thrust on the edge strips in the direction of its length.

2. The combination with a flexible poster, of a folding stretching member adapted to 120

exert an outward thrust at spaced points of tended and bowed outwardly from the 10
the poster and greater in length when ex- poster.
tended than the distance between said points, In testimony whereof I have hereunto set
